US00D816999S

(12) **United States Design Patent** (10) **Patent No.:** **US D816,999 S**
Zhang et al. (45) **Date of Patent:** **** May 8, 2018**

(54) **TOOTHBRUSH**

(71) Applicant: **Ranir, LLC**, Grand Rapids, MI (US)

(72) Inventors: **ZhaoQiang Zhang**, Jinagsu (CN);
Charles Jones, Warwickshire (GB);
Fiona Gale, Surrey (GB); **Travis**
Michael Spoor, Ada, MI (US);
Andreas Paul Lanvers,
Neunkirchen-Seelscheid (DE)

(73) Assignee: **Ranir, LLC**, Grand Rapids, MI (US)

(**) Term: **15 Years**

(21) Appl. No.: **29/596,156**

(22) Filed: **Mar. 6, 2017**

(51) LOC (11) Cl. **04-02**

(52) U.S. Cl.

USPC **D4/101**

(57) **CLAIM**

The ornamental design for a toothbrush, as shown and described.

DESCRIPTION

FIG. 1 is a perspective view of a toothbrush embodying the new design;

FIG. 2 is a right side view, the left side view being a mirror image thereof;

FIG. 3 is a front view thereof;

FIG. 4 is a top view thereof; and,

FIG. 5 is a bottom view thereof.

The portions shown in phantom lines in FIGS. 1-4 are shown for environmental purposes only and form no part of the claimed design.

1 Claim, 3 Drawing Sheets
